CLAIM

The ornamental design for a electrical cord strain relief end piece for a portable lamp or similar appliance, as shown and described.

DESCRIPTION

FIG. 1 is a top, rear, left side perspective view of an electrical cord strain relief end piece for a portable lamp or similar appliance showing my new design, the lamp being shown in broken lines for illustrative purposes only and forming no part of the claimed design; FIG. 2 is a left side elevational view thereof on an enlarged scale, the opposite side being a mirror image; FIG. 3 is a top plan view thereof on an enlarged scale; FIG. 4 is a bottom plan view thereof on an enlarged scale; FIG. 5 is a rear elevational view thereof on an enlarged scale; and, FIG. 6 is a front elevational view thereof on an enlarged scale.
